DESIGN FOR A COMPACT

Harry L. Berinstein, Elmira, N. Y.

Application October 7, 1935, Serial No. 58,878

Term of patent 3½ years

To all whom it may concern:

Be it known that I, Harry L. Berinstein, a citizen of the United States of America, residing at Elmira, in the county of Chemung and State of New York, have invented a new, original, and ornamental Design for a Compact, of which the following is a specification, reference being had to the accompanying drawing, forming part thereof.

I claim:

The ornamental design for a compact, as shown.

HARRY L. BERINSTEIN.
